US00D345143S

United States Patent [19]

Thomas

[11] Patent Number: Des. 345,143

[45] Date of Patent: ** Mar. 15, 1994

[54] **CENTRAL PROCESSING UNIT MODULE FOR A PROGRAMMABLE CONTROLLER**

[75] Inventor: **Sherman G. Thomas**, Earlysville, Va.

[73] Assignee: **GE Fanuc Automation North America, Inc.**, Charlottesville, Va.

[**] Term: **14 Years**

[21] Appl. No.: **639,998**

[22] Filed: **Jan. 11, 1991**

[52] U.S. Cl. **D13/162**

[58] Field of Search 361/380, 383, 391, 392,
361/393, 394, 395, 399, 415; D13/123, 162, 164,
184

[57] **CLAIM**

The ornamental design for a central processing unit module for a programmable controller, as shown and described.

DESCRIPTION

FIG. 1 is a left side elevational view of a central processing unit module for a programmable controller showing my new design wherein a conventional multi-pin connector is shown in phantom lines for information purposes only and forms no part of the claimed design; FIG. 2 is a front elevational view thereof; FIG. 3 is a right side elevational view thereof; FIG. 4 is a rear elevational view thereof; FIG. 5 is a bottom plan view thereof; FIG. 6 is a top plan view thereof; and, FIG. 7 is a rear and bottom perspective view thereof.

FIG. 1FIG. 2FIG. 3FIG. 4FIG. 5FIG. 6

FIG. 7
